UNITED STATES PATENT OFFICE

LYMAN L. LOFTON, OF ARDMORE, OKLAHOMA

COMBINED CHAIR AND STEPLADDER

Application filed November 5, 1930. Serial No. 493,620.

This invention has for its object the provision of an article of furniture which may be employed as a chair or quickly converted into a step ladder and which will be efficient in either use and which may be produced at a low cost. The invention is illustrated in the accompanying drawing and consists in certain novel features which will be herein-after first fully described and then more particularly pointed out in the appended claim.

In the drawing:

Figure 1 is a sectional elevation of an article embodying the invention, and

Fig. 2 is a front elevation of the same.

In carrying out the present invention, there are provided front legs 1 and rear legs 2 which converge upwardly and have their upper ends rigidly secured to a board or plate 3 which constitutes a portion of a chair seat. The front legs 1 are somewhat narrower than the rear legs 2 and are braced by a cross bar or rung 4 while the rear legs have secured to and extending between them a board or plate 5 which constitutes the lowest step of the ladder. Metal straps or bars 6 are secured to the legs upon their inner sides and serve to connect them and brace the structure. The board 3 is, of course, rigidly secured to the upper ends of the legs and to the rear edge of said board is secured, by hinges 7, a larger board 8 which is adapted to lie in a horizontal plane flush with said board 3 and constitute a chair seat, as will be understood upon reference to Fig. 1. Side bars 9 are secured to the edges of the member 8 at the rear end of the same and extend above and below said member, as clearly shown, the upper portions of said bars diverging upwardly so that when the device is arranged as a step ladder a firm support will be attained. Near their upper ends the side bars 9 are connected by cross bars 10 which are made slightly concave on their front faces

so that they will brace the side bars and also constitute a back for the article when it is used as a chair, the front concave faces of the bars fitting comfortably to the back of the user. Secured to the under side of the seat member 8 and converging toward the lower ends of the side bars 9 are braces 11, and to

the lower ends of said braces and the side bars is secured a board 12 which constitutes the uppermost step when the article is arranged as a step ladder. The step 5 projects somewhat to the rear of the rear edges of the legs 2, as clearly shown in Fig. 1, so that the step member 12 may rest at its front end upon the same when the device is arranged as a chair and will thereby aid in supporting the back and seat portions of the chair without excessive strain upon the hinges 7. The rear edges of the rear legs 2 and the front edges of the hangers or braces 11 are arranged obliquely upon the same angle of inclination so that the braces may abut and rest squarely against the legs when the device is arranged as a chair, as will be understood upon reference to the full lines in Fig. 1, and to maintain the parts against separation hooks 13 are pivoted upon the legs 2 and are engaged over studs or pins 14 upon the braces 11, as shown and as will be understood.

In Fig. 1, the device is illustrated in full lines arranged for use as a chair. When it is desired to use the article as a step ladder, the hooks 13 are released and the back and rear seat portion of the article are then swung over about the hinges 7 so that the seat member 8 will rest on the seat member 3 and the side bars 9 will rest upon the floor and constitute back legs for the ladder, as will be understood upon reference to the dotted lines in Fig. 1. In this position the step 12 will be disposed above the step member 8 and the under side of said seat member may be utilized as the tread surface of an intermediate step. Obviously, the device is very simple and compact and is strong and durable and will answer all the requirements of either a chair or a step ladder.

Having thus described the invention, I claim:

A combined chair and step ladder comprising front and rear pairs of legs converging upwardly, horizontal braces connecting said pairs of legs, an upper step member secured to the upper ends of said pairs of legs, an intermediate step member secured to and extending between the rear pair of legs and

resting on said horizontal braces, said intermediate step member projecting horizontally beyond the rear pair of legs, a seat member hinged to the upper step member, a step member disposed below the seat member and having its lower face resting upon the upper face of the intermediate step member adjacent their corresponding edges, obliquely disposed braces extending between said seat member and said step member and adapted to bear against the rear pair of legs, upwardly diverging side bars secured to the last mentioned step member and to said seat member and extending normally upwardly and rearwardly above the seat member, cross bars connecting the diverging side bars, hooks pivoted on the rear pair of legs between the upper step member and the intermediate step member, and keepers on the obliquely disposed braces engaged by said hooks.

In testimony whereof I affix my signature.
